[57] CLAIM

The ornamental design for a portable laptop computer, as shown and described.

DESCRIPTION

FIG. 1 is a front, top and right side perspective view of a portable laptop computer showing our new design; FIG. 2 is a rear, bottom and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, top and right side perspective view thereof with a pivotable combined cover and display pivoted into closed, keyboard overlying position.

FIGS. 3-9 are drawn on an enlarged scale.
